U.S. Appl. No. 29/912,837, filed Sep. 25, 2023.

Primary Examiner — Nathan M Johnston

CLAIM

The ornamental design for a handheld drug delivery device as shown and described.

DESCRIPTION

FIG. 1 is a perspective view showing a new design for a handheld drug delivery device;

FIG. 2 is a front view of the handheld drug delivery device of FIG. 1;

FIG. 3 is a rear view of the handheld drug delivery device of FIG. 1;

FIG. 4 is a right-side view of the handheld drug delivery device of FIG. 1;

FIG. 5 is a left-side view of the handheld drug delivery device of FIG. 1;

FIG. 6 is a top view of the handheld drug delivery device of FIG. 1; and,

FIG. 7 is a bottom view of the handheld drug delivery device of FIG. 1.

The broken lines are included for the purpose of illustrating portions of the design that form no part of the claimed design.

1 Claim, 4 Drawing Sheets
